UNITED STATES PATENT OFFICE.

JAMES M. DODGE, OF PHILADELPHIA, PENNSYLVANIA, ASSIGNOR TO LINK-BELT COMPANY, OF CHICAGO, ILLINOIS, A CORPORATION OF ILLINOIS.

CHAIN.

958,676.

Specification of Letters Patent. Patented May 17, 1910.

Application filed November 6, 1909. Serial No. 526,536.

To all whom it may concern:

Be it known that I, JAMES M. DODGE, a citizen of the United States, residing in Philadelphia, Pennsylvania, have invented 5 certain Improvements in Chains, of which the following is a specification.

The main object of my present invention is to economize in the manufacture of a chain of this type by forming the segmental 10 projections on the link integral with the link, forming the said projections from the material punched from the link to form the pivot pin opening.

A further object of the invention is to provide 15 an intermediate bearing on the links which will, in conjunction with the segmental projections, space the links apart, so that the side bearing of one link against another is provided, thus considerably reducing 20 the friction and wear upon the links.

A still further object is to strengthen the link as fully described hereafter.

In the accompanying drawings:—Figure 1, is a longitudinal sectional view on the line 25 1—1, Fig. 2, of a chain made in accordance with my invention; Fig. 2, is a sectional plan view on the line 2—2, Fig. 1; Fig. 3, is a perspective view of one of the links; Fig. 4, is a side view of one of the link 30 blanks; Fig. 5, is a sectional view of the link blank after being struck up; Fig. 6, is a sectional view of the link blank after coining; Fig. 7, is a sectional plan view of a link 35 showing a section of chain without the intermediate bearing; Fig. 8, is a perspective view illustrating one of the links of the chain shown in Fig. 7; Figs. 9, 10 and 11, are views illustrating modifications; Figs. 12, 13, 14, 15 and 16, are views illustrating 40 my invention applied to a rocker joint chain; and Fig. 17, is a view showing the extended bearings on both sides of a link.

Referring in the first instance to Figs. 1 and 2, A is a link composed of a series of 45 link elements A', and B is a link composed of a series of link elements B'. The number of link elements will vary, according to the width of chain necessary.

The links are coupled together by pivot 50 pins D and these pivot pins are free to rotate in the links and are provided with washers d, d at each end, which overlap the links, and the pins are preferably riveted.

It will be understood that other means of 55 fastening may be resorted to without depart-

ing from the essential features of the invention.

The link elements A' and B' are identical, so that only one set of dies is required in making the series of links. Each link has 60 an opening at each end, and this opening is formed by punching the metal from the link, the link itself being punched from a suitable blank. Projecting laterally from the side of each link element A' are extended bearings a' and these bearings are formed of laterally bent portions punched out of the blank in forming the openings a, and the link element B has similar extended bearings b' 65 also formed by laterally extended portions 70 of the blank punched from the openings b.

It will be seen by referring to Fig. 2, that these extended bearings project into the openings of adjoining links and bear upon 75 the pins, giving to their particular links, in the present instance, double the bearing that a link without the lateral projections would have.

I preferably so proportion each extended bearing that it will be longer than the thickness of the link through which it extends, so that when the several links are assembled, as in Fig. 2, there will be a clearance between the sides of the adjoining links which have 80 independent rotary movement on the pivot, 85 thus eliminating side friction and consequently wear.

In some instances, particularly in links of the larger sizes, I preferably form a projection e on each link element, midway between 90 the openings in the link, as illustrated in Fig. 3. This projection is formed by bending up the metal in the space between the teeth of the link, as illustrated in Fig. 4, which shows a link blank before receiving 95 the final bend. This projection extends preferably the same distance from the link element as the extended bearings a', b', so that when the links are assembled, as in Fig. 2, they are separated for the purpose described 100 above; the links having a three point contact. The side bearings are struck up from the metal of the link in such a manner as to form shoulders which limit the movement of the links on the pins.

The central projecting member may be made as shown in Fig. 3, by turning up the metal forced from between the teeth of the link, or may be pressed out from the body 105 of the link, as at e', Figs. 9 and 10, or the 110

link may have a rib e^2 at the upper edge as in Fig. 11, or have the rib e^2 and the projection e ; in each case the ribs or projections act as stiffening members to strengthen the link and will resist lateral strains or the tendency to bend due to longitudinal strains.

In Fig. 12, I have shown my invention as applied to a rocker joint chain, in which the link members A^2 and B^2 have their extended 10 rocker bearings a^3 and b^3 formed by metal forced from the rocker opening and bent, as clearly shown, giving an extended bearing and making the bearing integral with the link element. In this instance the several 15 link elements A^2 are connected by transverse rivets or pins a^4 and the link elements B^2 are connected by transverse pins or rivets b^4 .

In Fig. 14, I have shown a modification of a rocker chain in which the pins b^5 of 20 the elements B^3 pass through slots a^5 in the elements A^3 , and pins a^6 pass through slots b^6 in the elements B^3 . The connecting pins are arranged at each side of the rocker joint, as shown.

In Figs. 12 and 13, I have shown each link 25 provided with a rocker member bent up from the metal of the link, but in Fig. 15, I have shown the links A^5 and B^5 as each having an extended bearing a^7 at one end 30 and a punched opening at the other end, with rocker pins c inserted as shown, so as to connect successive links; each of said pins extending through the punched openings and being attached to the link element B^5 in any 35 suitable manner, so as to be capable of rocking upon the extended bearing a^7 .

It will be understood that either the seat 40 surface or the rocker surface may be made in the form of a pin separate from the link element; the other contacting surface being integral with its link, and in either case the spindle part may serve as a rivet.

In some instances, as shown in Fig. 17, I 45 may form the extended bearing surface on both sides of the link by pressing the metal from the opening, partly on one side and partly on the other. This is preferably done cold by the coining process.

I claim:—

50 1. A chain made up of a series of link elements, each link element having lateral projections extending through others of said links and of a length greater than the width of the element through which it extends, so 55 that when the link elements are assembled the said lateral projections will space the said elements apart so as to avoid side friction and wear.

2. A chain made up of a series of link 60 elements having openings and lateral extensions at the said openings, pivot pins, said extensions forming extended bearings for the pivot pins and projecting through openings in adjoining elements, the said extensions being greater in length than the width 65

of the element through which they extend, so as to space the elements apart to prevent side friction and wear.

3. A chain link element having pivot pin 70 openings, laterally extended bearings, and an intermediate projection of the same length as said bearings.

4. The combination in a chain of a series 75 of link elements; and means for connecting said elements; each link element having openings adjacent its ends and being provided with lateral projections adjacent said openings; there being a lateral projection at the middle of each link element placed to co-act with a similar projection of an 80 adjacent element.

5. A link element having openings for 85 pivot pins and lateral extensions projecting at right angles to the plane of the link element, with an integral projection intermediate said bearings.

6. A chain consisting of a series of link 90 elements, each having lateral projections extending through the adjacent elements and greater in length than the width of the elements through which they pass, with means for holding the link elements together.

7. A chain link element having two teeth and two pivot openings, lateral integral projections adjacent the openings, and a lateral 95 projection at a point on the link element midway between the teeth.

8. A chain link element consisting of a plate having pivot pin holes, lateral projections adjacent said holes, and a lateral 100 projection from one edge of the plate intermediate said holes.

9. A chain consisting of a plurality of 105 link elements, certain of said elements having laterally extended bearings projecting into openings in others of said elements, the extension of said bearings beyond the sides of their link elements being greater than the thickness of the link elements into which they extend.

10. The combination in a chain of a plurality of link elements connected together and having openings, means for connecting the link elements, certain of said link elements having lateral projections abutting 115 on other link elements and of a length greater than the thickness of the link elements with which they co-act.

11. The combination in a chain of a plurality of pairs of link elements and means 120 pivotally connecting said pairs of elements, the elements of certain pairs having lateral abutting portions maintaining them at a distance apart greater than the thickness of the pairs of link elements with which they 125 co-act.

12. The combination in a chain of a plurality of links each consisting of a pair of link elements, the elements of alternate links lying outside the elements of the 130

adjoining links, each pair of link elements having openings and lateral projections extending through the openings of the adjoining link elements, said projections being of greater length than the thickness of the elements 5 of the elements through which they extend.

13. The combination in a chain of a plurality of links each consisting of a pair of link elements, the elements of alternate links 10 lying outside the elements of the adjoining links, each pair of link elements having openings and lateral projections extending through the openings of the adjoining link

elements, said projections being of greater length than the thickness of the elements 15 through which they extend, with abutting lateral projections on certain of the links intermediate the openings therein.

In testimony whereof, I have signed my name to this specification, in the presence of 20 two subscribing witnesses.

JAMES M. DODGE.
